US0D1091479S

(12) **United States Design Patent** (10) **Patent No.:** **US D1,091,479 S**
(45) **Date of Patent:** **** Sep. 2, 2025**

(54) **SOCKET**

(71) Applicant: **Hongjia Ma**, Shantou (CN)

(72) Inventor: **Hongjia Ma**, Shantou (CN)

(**) Term: **15 Years**

(21) Appl. No.: **29/985,096**

(22) Filed: **Jan. 16, 2025**

(30) **Foreign Application Priority Data**

Dec. 31, 2024 (CN) 202430843403.7

(51) **LOC (15) Cl.** **13-03**

(52) **U.S. Cl.**

USPC **D13/139.8**

(57) **CLAIM**

The ornamental design for a socket, as shown and described.

DESCRIPTION

FIG. 1 is a perspective view of a socket showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion "9" shown in FIG. 1.

The dash-dash broken lines in the drawings depict portions of the socket that form no part of the claimed design. The dash-dot-dash broken line portion of the figure drawings is included to show boundaries of the enlarged views that form no part of the claimed design.

1 Claim, 9 Drawing Sheets
